(57) **CLAIM**

The ornamental design for an in-car speaker grill, as shown and described.

DESCRIPTION

FIG. 1 is a front view of an in-car speaker grill showing my new design;

FIG. 2 is a rear view from the rear of the in-car speaker grill in FIG. 1;

FIG. 3 is a top view of the in-car speaker grill in FIG. 1 and FIG. 2;

FIG. 4 is a bottom view of the in-car speaker grill in FIG. 1 and FIG. 2;

FIG. 5 is a right side view of the in-car speaker grill in FIG. 1 and FIG. 2; and,

FIG. 6 is a left side view of the in-car speaker grill in FIG. 1 and FIG. 2.

The broken lines are for illustrative purpose only and form no part of the claimed design. What is illustrated by the broken lines is a grill net.

1 Claim, 6 Drawing Sheets(56)
